(57) **CLAIM**

The ornamental design for a vehicle grille, as shown and described.

DESCRIPTION

FIG. 1 is a front perspective view of a vehicle grille attached to a vehicle, no part of the vehicle is claimed;

FIG. 2 is a front elevational view of the vehicle grille;

FIG. 3 is a top plan view of the vehicle grille;

FIG. 4 is a bottom plan view of the vehicle grille; and,

FIG. 5 is a left side elevational view of the vehicle grille (the right side view is a mirror of the left side view and is not shown).

The broken lines are for illustrative purposes only and form no part of the claimed design.
